UNITED STATES PATENT OFFICE.

HORACE G. WOODHEAD, OF CHICAGO, ILLINOIS.

CLAMP.

1,243,027.

Specification of Letters Patent.

Patented Oct. 16, 1917.

Application filed March 25, 1915. Serial No. 16,869.

To all whom it may concern:

Be it known that I, HORACE G. WOODHEAD, a citizen of the United States, residing at the city of Chicago, in the county of Cook and State of Illinois, have invented 5 certain new and useful Improvements in Clamps, of which the following is a specification.

My invention relates to devices which are 10 used for holding bags or sacks while being filled with grain or other material, whether such receptacles are filled from spouts by which the material is led to them by gravity or whether the material is placed therein by 15 the shovel, it is important that they be securely held and that they shall not be torn or otherwise injured by the holding device. The object of the invention is to provide means by which the bags or sacks may be 20 securely held in the open position without danger of injury thereto. And, while so providing, I also am able to furnish a strong, cheap and simple device which is easily manipulated to attach the bag thereto and 25 from which it may readily be detached.

The principles of my invention are illustrated in the drawings, in which—

Figure 1 shows a front view of my improved bag holder;

Fig. 2 is a side view thereof;

Fig. 3 is a bottom view of Fig. 1, showing in section a bag in place thereon, and

Fig. 4 is an enlarged view of a cam-lever by which the bag is secured or released.

Further describing my invention by reference to the drawings in which like characters of reference denote like parts throughout.

1 is a downspout or pipe connecting with 40 a storage bin, and 2 a valve by which the flow of grain can be controlled. 3 is the metal frame of my device, having a recessed portion and preferably a back wall 4, the lower part of the downspout being cut away 45 to receive the same. 5 and 6 are flanges outwardly projecting from the frame 3. A stub shaft 7 is journaled in the said flanges and the lower part thereof is provided with a yielding abutment head 8, preferably consisting of a wire coil whose periphery is set

out from the central shaft to allow elastic movement toward the same. A member correlative to that last described comprises a shaft 9, which is similarly journaled in the 50 flanges 5 and 6, and a cam offset body portion 10, having a roughened or knurled face

11. To the shaft 9 is attached a handle 12, secured against rotation thereon and with it forming a cam-lever. The relation of the handle to the body portion of such cam-lever is indicated by the full and dotted lines shown in Fig. 1, and as hereinafter described.

The lower portions of the downspout should be provided with stationary bag retaining devices. Appropriate to this purpose are the corner brackets 14, 15, and 16, provided with the outwardly projecting flanges 14', 15', 16' and 17'.

When it is desired to attach a bag to the structure shown, the cam-lever is thrown to the position shown in the dotted lines in Fig. 1, and the open mouth of the bag is placed over the lower part of the downspout, beginning at the rear and engaging 65 with the flanges 15', 17'. It is brought forward around the front brackets 14 and 16, and the loose material or bight of the bag is carried between the head 8 and the offset portion of the cam-lever, the recess 4 facilitating this operation. The handle 12 is then turned to the full line position shown in Fig. 1, thereby gripping the loose portion of the bag top between the members 8 and 10. The relation of the handle 12 to the 70 face 11 is such that in this operation the point of greatest eccentricity of the latter is carried past the line drawn transversely through the axes of the shafts 7 and 9, accommodating therefor being provided by the 75 resiliency of the head 8. The bag is thereby drawn tightly around the spout and securely held in that position. The reverse movement of the lever frees the bag and leaves the mechanism in position to receive 80 the next bag which is to be filled.

While I have illustrated my invention in its application to a stationary spout, it is evident that it is equally applicable to a movable standard if so desired.

I claim:

1. In a clamp; a gripping device consisting of an elastic head and a cam-lever revolvably mounted adjacent to and engageable with said head to positively move the 105 same.

2. In a clamp; a gripping device consisting of a revolvble elastic head and a cam-lever revolvably mounted adjacent to and engageable with said head to positively move 110 the same.

3. In a clamp; a gripping device consist-

ing of a revoluble elastic head of coiled spring wire and a cam-lever revolvably mounted adjacent to and engageable with said coiled wire to clamp material therebetween.

4. A clamp including a frame, a lever having an eccentric head journaled on the frame, and an elastic abutment device adapted yieldingly to receive material placed between the same and said eccentric head and to coöperate therewith to hold the said material when said head is rotated past its dead center, the compressive force between the elastic abutment and the eccentric head being controlled by the continued movement of the eccentric head.

5. A clamp including a frame, a lever having an eccentric head journaled on the frame, and a coiled wire abutment device adapted yieldingly to receive material placed between the same and said eccentric head and to have the convolutions of the abutment engaged by said eccentric head to hold the said material when said head is rotated past its dead center.

6. A clamp including a frame, a lever having a cam head journaled on the frame, and

an elastic coiled member adapted yieldingly to receive material placed between the same and said cam and to coöperate therewith to hold the said material when said head is rotated past its dead center.

7. A clamp including a frame, a pair of parallel shafts journaled in said frame, and movable coöperating rigid and yielding abutments carried by said shafts respectively.

8. A clamp including a frame, a shaft carried by said frame, a coiled wire carried by said shaft with the convolutions normally spaced from said shaft, and means coöperating with the coiled wire adapted to engage the same to move the convolutions at one side of the shaft into closer relationship therewith.

In witness whereof, I have hereunto subscribed my name this 16th day of March, 1915, in the presence of two subscribing witnesses.

HORACE G. WOODHEAD.
